UNITED STATES PATENT OFFICE.

JOHN A. MCFERRAN AND MILTON L. MCFERRAN, OF LOUISVILLE, KENTUCKY.

DRAFT-REGULATOR AND SMOKE-PURIFIER.

1,142,721.

Specification of Letters Patent.

Patented June 8, 1915.

Application filed October 30, 1914. Serial No. 869,463.

To all whom it may concern:

Be it known that we, JOHN A. MCFERRAN and MILTON L. MCFERRAN, citizens of the United States, residing at Louisville, in the 5 county of Jefferson and State of Kentucky, have invented certain new and useful Improvements in Draft-Regulators and Smoke-Purifiers; and we do hereby declare the following to be a full, clear, and exact description of the invention, such as will enable others skilled in the art to which it appertains to make and use the same.

This invention relates to draft regulators and smoke purifiers for steam boilers, and 15 one of the principal objects of the invention is to increase the combustion of the fuel with a view to eliminating the smoke and economizing in the use of the fuel.

Another object of the invention is to provide simple, reliable and efficient means for 20 utilizing all the heat units of the fuel by introducing hot air or oxygen over the fire-bed to mingle with the hot gases liberated from the burning fuel and to thus aid the 25 combustion and eliminate the smoke.

The foregoing and other objects may be attained by means of the construction illustrated in the accompanying drawings, in which,

30 Figure 1 is an elevation of the end of a locomotive boiler and showing the fire door open, Fig. 2 is a front end elevation of the boiler, Fig. 3 is a detail plan view of the spring actuated rod for operating the intake valves, Fig. 4 is a detail view of the weighted lever connected to the fire-door for operating the regulator, and said bar being connected by chains to the spring actuated rod, shown in Fig. 3, Fig. 5 is a top plan 35 view of the firebrick wall over the grate bars, and showing the hot-air pipes broken away, Fig. 6 is a fragmentary vertical section taken through the front end of the boiler and through the smoke box, Fig. 7 is 40 a sectional view showing one of the intake or butterfly valves, Fig. 8 is a front elevation of the regulator with the cover removed, Fig. 9 is a vertical sectional view of the same, Fig. 10 is a fragmentary side elevation showing a modified form of the invention, and Fig. 11 is a front end elevation 45 of the boiler.

The invention is shown in connection with a locomotive boiler, but it will be understood that the invention may be applied

to any form of boiler, whether stationary or not.

Referring to the drawing, the numeral 1 designates a locomotive boiler and 2 is the head provided with a hinged fire-door 3. 60 At front end of the boiler are provided a plurality of intake bells 4, each comprising a downwardly extending pipe and pivotally mounted within the horizontal portion of said pipe is a butterfly valve 5 provided with openings 6 at opposite sides thereof and said valve is mounted upon a stem 7 which is pivoted in the intake pipe, at right angles to the intake pipe to close the same excepting for the opening 6. 70

Four intake pipes are connected to the bells 4 and these pipes curve around the inside of the smoke box 9, as shown in dotted lines in Fig. 2, and as indicated by the reference numerals 8, 10, 12 and 13, said pipes 75 being connected to a cross pipe 14, and the pipes 15 communicate with said cross pipe 14. The pipes 15 are provided with nipples 17 which extend into the brick arch 16.

A sliding rod 19, mounted in brackets 20 80 at the front of the boiler is provided with an encircling spring 21 secured at one end to said rod and at the other end bearing against one of the brackets 20 and said rod is connected to the crank 22 attached to the 85 valve stems 7. A bell crank lever 23 pivoted at 24 is provided with a slot 25 through which a pin 26 extends, said pin projecting from the rod 19. Connected to one arm of the bell crank lever 23 is chain 27, said chain extending to a lever 28 connected to the fire-door 3, said lever 28 being mounted to slide in hooks 29 and provided with a ball or weight 30 at its outer end. The lever 28 is provided with an inclined 95 portion 31 on which the door 3 rides when it is open to tilt the lever 28, said lever being provided with a squared opening for receiving the squared projection 32 on the main shaft 33 of the regulator about to be 100 described.

The regulator comprises a casing 34 in which is mounted the shaft 33 and said shaft carries a gear wheel 35, which meshes with a pinion 36 on a shaft 37. Mounted 105 on the shaft 37 is a gear 38 which meshes with a pinion 39 on the escapement shaft 40. An escapement wheel 41 is mounted on the shaft 40 and a verge 42 carried by a pendulum 43 engages the escapement wheel 41 and 110

serves as a counterbalance to the weight 30. Connected to the pendulum 43 is an adjustable weight 44.

The hook 29 is formed on a rod 45 which 5 is connected to a bell crank lever 46 pivoted at 47, said bell crank lever having a rod 48 connected thereto, and said rod extending through the blower valve 49. The valve 49 is mounted on a pipe connection 50, which 10 communicates with a pipe 51 leading to a blower 52 disposed immediately under the intake end of the smoke stack 11. A foot lever 53 connected to the rod 45 and pivoted at 54, is provided with a pedal 55 which may 15 be operated by the engineer independent of the opening of the fire door 3.

When the door 3 is opened the rod 28 is thrown upward at the weighted end 30 which slackens the chain 27 thus permitting the 20 chain 21 to slide the rod 19 and open all the valves 5 to permit the air to enter the smoke box and be heated to a high degree before it is discharged through the pipes and through the nipples 17 into the fire-box. After the 25 door 3 has been closed, the regulator serves to hold the lever 28 from immediately dropping to its initial position owing to the action of the pendulum and the escapement. After the valves 5 have been closed, there is 30 a restricted opening through the port 6 for a constant supply of air to the fire-box. It will be understood that the engineer can place his foot upon the pedal 55 at any time and open the valve whether the fire-door 3 35 is open or not.

In the modification shown in Figs. 10 and 11, the invention is shown applied by dispensing with the brick arch and showing the connections made on small engines which 40 have the steam jet system, thus reducing the cost of the application of this invention. The intake bells 4 are connected to the pipe 56 which leads to a header 57 in the smoke box and thence leading to the radiator pipe 45 58 which discharges into the fire-door opening at 59.

From the foregoing it will be obvious that 50 hot air and oxygen is fed over the fuel at the required times and in such quantities as will insure a complete combustion of the fuel and thus eliminate smoke.

Copies of this patent may be obtained for five cents each, by addressing the "Commissioner of Patents, Washington, D. C."

Various changes may be made in the details of construction without departing from the spirit and scope of the invention as defined in the claims.

The invention may be applied to any form of boiler without material change in the different parts.

What is claimed is:

1. A draft regulator and smoke eliminator comprising a series of intake pipes, valves in said pipes, said pipes leading into the smoke box and from thence through into the fire-box, and means for discharging the heated air and oxygen over the fire grate, a fire door, and connections between said fire-door and the intake valves to open the latter when the fire-door is opened and a regulator to prevent the valves from being closed immediately when the fire-door is closed.

2. A draft regulator and smoke purifier comprising air inlet pipes, valves in said pipes, a spring actuated rod for controlling said valves, said intake pipes leading through a smoke box, a brick bridge in the fire-box, 75 said pipes discharging through said brick bridge, a fire-door, connections between said fire-door and said spring actuated rod for opening the valves when the door of the fire-box is open, a regulator comprising a clock 80 movement for preventing the intake valves from closing suddenly and a force draft blower for increasing the draft through the smoke stack.

3. A draft regulator and smoke purifier 85 comprising air inlet pipes, valves in said pipes, said pipes leading through a smoke box, a bridge in the fire-box, said pipes discharging through said bridge, a fire-door, 90 and connections between said fire-door and said valves, a clock movement for preventing the valves from closing suddenly, and a force draft blower for increasing the draft through the smoke stack.

In testimony whereof we affix our signatures in presence of two witnesses.

JOHN A. McFERRAN.
MILTON L. McFERRAN.
